GLOVE

Julius A. Higier, Johnstown, N. Y.

Application December 3, 1956, Serial No. 44,052

Term of patent 3½ years

(Cl. D3—11)

I claim:

The ornamental design for a glove, substantially as shown.
